PLUNGER FOR CLOSURE OF A GAS HOLDER

Friedrich Einbeck, Dortmund, Germany, assignor
to the firm Aug. Klönne, Dortmund, GermanyApplication November 8, 1934, Serial No. 752,145
In Germany March 22, 1934

2 Claims. (Cl. 48—176)

The invention relates to gas-holders of the kind in which closure at the top is made by a cover in the form of a piston, no water seal being used.

5 In connection with such gas holders it has been proposed to provide the piston with two separate packing rings, one above the other, the lower ring being normally out of contact with the wall of the gas holder, and being only brought into contact with the wall when the upper ring is worn and must be removed for repair or renewal. This enables the gas holder to continue in operation while the top ring is removed. The bottom ring lasts for a very long time, as it is only used 10 for short periods at long intervals.

15 According to my invention two dilatable packing rings are connected to each other by flexible or elastic gas tight means, and are radially movable in relation to each other, the lower ring having also a gastight connection to the piston allowing it to be moved into and out of its operative position.

20 Normally, when the top ring is in operation, escape of gas is prevented by this ring together with the elastic connection between the two rings 25 and the gas tight connection of the lower ring to the piston. When the top ring is to be removed the lower ring is first moved into its operative position, and the top ring can then be retracted and taken out, without allowing any 30 escape of gas.

35 In practice I may with advantage use an elastic web attached to the top ring and the bottom ring and extending downwards from the latter to the rim of the piston, its lower part forming the flexible, gas-tight connection between the lower ring and the piston.

The dilatable packing rings may be constructed, for example, in the manner shown by the prior 40 United States Patent No. 1,693,468, wherein an endless packing ring (made of a cotton textile ring inlaid with rubber or of similar materials) is supported by a flexible and dilatable sheet-metal ring.

45 Various devices may be used for pressing the rings against the wall of the gas holder. Springs or weighted levers may serve for this purpose, as shown in the United States Patent No. 1,693,468. A convenient device consists of a weighted lever to which both rings are connected by approximately horizontal bars adjustably fastened to the lever.

50 The invention is illustrated in the annexed drawing, showing one form of construction, Fig. 1 being a diagrammatic vertical section, and

55 Figs. 2 and 3 being sectional views, to a larger scale, showing the two alternative positions of the rings.

The piston *k* is vertically guided in the gas chamber *w* by means of rollers *r*. A gastight, flexible or elastic web connects the top and bottom packing rings *o*, *u* to each other and to the rim of the piston *k*.

5 The dilatable rings are connected by bars *h*¹ to a lever *h* weighted by a weight *g*. Each bar has two or more holes enabling it to be adjustably connected to the lever by means of a peg.

Fig. 2 shows the top ring in operative position, 10 with the lower ring retracted, for normal working of the piston. Fig. 3 shows the top ring retracted, with the lower ring in operative position, the connections of the bars *h*¹ to the lever *h* having been changed for that purpose. In this position the top ring can be removed, for insertion 15 of a fresh ring. As already mentioned, retraction of the top ring does not take place till the bottom ring is in operative position, so that there is no escape of gas. The bottom ring is 20 retracted again when a fresh top ring has been inserted and brought into contact with the wall, so that the amount of wear to which the bottom ring is subjected is very small, and its life is 25 very long.

I claim:—

1. In a gas holder of the waterless type, a piston, a pair of separate and dilatable packing rings mounted in said piston arranged one above the other and adapted to make sealing contact 30 with the wall of the gas holder, means enabling either ring to be retracted radially from the wall of the gas holder while the other ring remains in contact with said wall, and a flexible web connecting said rings with each other and the piston 35 in such a manner as to enable said rings to move radially and independently of each other between sealing and idle positions.

2. In a gas holder of the waterless type, a piston, a pair of separate and dilatable packing 40 rings mounted in said piston arranged one above the other and adapted to make sealing contact with the wall of the gas holder, levers pivoted to the piston and each having a vertical arm extending behind said rings, horizontally guided 45 arms attached to each ring to provide for movement of the ring and arms in a radial direction, connections between each of said horizontal arms and corresponding vertical lever arms enabling either ring to be connected independently of the 50 other to the levers in sealing and retracted position as desired, means applying pressure to said levers to force whichever ring is in sealing position, into sealing contact with said wall, and a flexible web connected to the two packing rings 55 and to the peripheral edge of the piston.

FRIEDRICH EINBECK.
